UNITED STATES PATENT OFFICE.

WILLIAM E. SULLIVAN, OF JACKSONVILLE, ILLINOIS.

TURNUCKLE.

1,420,460.

Specification of Letters Patent. Patented June 20, 1922.

Application filed March 9, 1922. Serial No. 542,332.

To all whom it may concern:

Be it known that I, WILLIAM E. SULLIVAN, a citizen of the United States of America, and a resident of Jacksonville, county of 5 Morgan, State of Illinois, have invented a new and useful Improvement in Turnbuckles, of which the following is a specification.

This invention relates to tensioning means of general application for tightening rods, 10 cables and the like, as in connection with circus paraphernalia and various temporary frame devices and including heavy knock-down structures and vehicles. More specifically the invention relates to turnbuckles and 15 the like.

Turnbuckles of ordinary form are subject to certain limitations and inconveniences, as for instance, on heavy work a wrench is usually necessary to turn the link. Moreover 20 the threaded members or stub ends and also the link have to be made rather long in order to take up the slack and stretch, especially if the cable is long. If many turnbuckles have to be set a large amount of time and labor 25 are involved.

The main objects of the invention are to provide a quick acting take-up means of improved form for eliminating the slack in cables and the like; to provide a turnbuckle 30 of the character described having a leverage take-up member or folding joint mechanism; to provide a turn buckle of this character adapted for operation in the usual manner, that is by screw adjustment, to attain an initial or preliminary degree of tension and 35 corresponding setting, and by leverage action adapted for quick operation to throw full tension upon the member to be drawn taut, and adapted for reverse operation in 40 loosening; and to provide in such a device coacting jaw members arranged to receive the full tension of the device and so relieve the take-up lever when the device is set.

An illustrative embodiment of this invention is shown in the accompanying drawings, in which:

Figure 1 is an edgewise view of the turnbuckle with the leverage part in its drawn up or shortened position.

Fig. 2 is a side view thereof.

Fig. 3 is a longitudinal section on the line 3—3 of Fig. 1 with the leverage part in its opened or elongated position.

Fig. 4 is a section on the line 4—4 of 55 Fig. 3.

In the construction shown in the draw-

ings the take-up device is in the form of a turnbuckle having a lever embodied in the link member. The take-up as a whole comprises mainly a hook stub end 1, an eye stub 60 end 2, a lever 3 and a special form of split link consisting of a pair of hook-like jaws 4 operatively connected by said lever and having the stub ends 1 and 2 screw connected to their outer ends as at 5. The lever 65 3 is pivotally connected, as at the points 6, to both jaws. The jaw members are of U-shape with the threaded perforation 5 at the bend and with a hook at the end of each arm, said hooks being similar, and turned in 70 the same direction, with a bearing shoulder 7 in a plane about perpendicular to the main axis of the turnbuckle. The pivots are formed integrally on the innermost tips of the jaws, as well shown in Fig. 3, and project outwardly to receive the correspondingly apertured ends of the U-shaped lever 75 3. In order to render the connection secure and permanent the tips of the pivots 6 are riveted or spun over, as shown in Fig. 4. 80

The jaw hooks are each formed with a tip substantially in alignment with the shank of the corresponding arm and with the adjacent part bent out of alignment and to provide the seat 7 which is to receive the corresponding tip of the coacting jaw when the leverage mechanism is set in its take-up position. 85

In order to provide for free passage of the jaw tips past each other in locking and unlocking, and for positive mutual bearing of 90 the jaw shoulders 7 on each other in stable tension relation when the device is set in its take-up position I secure the necessary clearance by forging each hinge pivot on the extreme corner of the corresponding jaw tip 95 away from the seat 7, and I arrange the two apertures 6' on each arm of the lever 3 somewhat out of alignment with the main body or shank of said lever, so that when the handle part of the lever is pulled back to its effective position it will snap past the critical point and permit the jaw shoulders 7 to meet squarely in load carrying position. In order to assure full release of pressure on the pivots when the jaws are set, the bend of the lever is 105 bowed sidewise somewhat at 8 so as to let the long arm or handle of the lever swing inward far enough to carry the pivots 6 well past the main axis or tension line of the device, and so permit the shoulders 7 to come 110 together.

The jaws may be drop forged if desired and

2
may be made of either malleable iron or cast steel. In any event the rivets are best made integral with the jaws. The lever is drilled in a jig and then spread over the rivets which are then spun down in a rivet spinner, or hammered down in a riveting machine. The jaw members 4 are formed and finished alike in a jig and the ends threaded right and left handed respectively.

10 This turnbuckle takes the place of a standard turnbuckle, being the same length when locked and takes the same size of threaded ends or stubs.

15 All sizes can be made interchangeable with the standard turnbuckles commonly in use.

20 This turnbuckle is used especially in the construction of Ferris wheels and the like. They are used in the bracing and torsion members of the wheel. The hook stub hooks 25 in the steel part of the wheel and a small wire cable with a hook attached to the end hooks into the eye end of the turnbuckle.

25 It will be seen that in taking down the wheel it is important to take it down in the shortest possible space of time and erect it the same way. I find that by making these cables all in jigs so that they have exactly 30 the same space left for the turnbuckle that the turnbuckles can all be made alike and, therefore, they are all interchangeable. To illustrate, in taking down a certain standard wheel, there are forty-eight turnbuckles to take out of the different bracing cables and none of these turnbuckles need to be unscrewed to take them out as the present 35 turnbuckle must be. The old turnbuckle must be unscrewed until the hook will unhook from the steel member to which it is fastened, and as the wire cables spring more or less that requires more unscrewing. With 40 this buckle the lever can be thrown over and the buckle expands an inch and a half, which allows it to unhook at once and does not change the threads or the length of the buckle.

45 Then when the operator wishes to re-erect, his cables are all the same length and the turnbuckles all the same length. Then the turnbuckles can be hooked in any space and when the lever is turned over, locking the buckles together, the cables are 50 not only tightened to any tightness desired but the wheel automatically becomes true just as it was when set up before. This practically avoids all trueing up, but if trueing up is needed instead of having to turn the turnbuckle with a wrench or pin, the lever can be thrown over relieving the strain and the turnbuckle very readily turned to the desired tension and the lever pulled down 55 making the proper adjustment. This is much more rapid than the old turnbuckle, and in fact in putting in forty-eight turnbuckles it saves a great deal of time.

60 This turnbuckle is a great time and labor saver not only in erecting or taking down a

Ferris wheel but for practically all portable riding devices; merry-go-rounds of all kinds; circle swings of all kinds; the "whip"; the "frolic"; and many other portable riding devices. This turnbuckle can 70 also be used to great advantage in aeroplanes or airships when they are taken down to be moved or shipped in cars and reassembled again.

75 Although but one specific embodiment of this invention is herein shown and described, it will be understood that numerous details of the construction shown may be altered or omitted without departing from the spirit of this invention as defined by the following 80 claims.

I claim:

1. A self locking turnbuckle comprising a pair of threaded stub ends and a split link to the respective parts of which said 85 stub ends are secured, said link comprising a pair of coacting jaw members and a lever operatively connected to said jaw members to engage and disengage the latter.

2. A self locking tension take-up device 90 comprising a pair of hook members having coacting jaw shoulders, in combination with a lever pivotally connected to the tips of said jaw shoulders and arranged for snapping past the main tension axis when forced to its 95 effective position to throw said shoulders into bearing engagement.

3. A tension take-up device comprising a pair of hook members having coacting jaw shoulders disposed about squarely across 100 the main axis of said device, in combination with a lever pivotally connected to the tips of said jaw shoulders and arranged for snapping past the main tension axis when the device is drawn taut to throw said shoulders 105 into bearing engagement.

4. A self locking, quick acting turnbuckle including a pair of complementary coacting hook members each provided with pivots formed integrally on the tips of the hooks, 110 and a lever apertured adjacent to one end to receive said pivots in spaced operative relation whereby the hook members may be pulled together and the hook faces thrown into mutual bearing engagement to relieve 115 the pivots.

5. A quick acting take-up device for tension members comprising a pair of hook members each provided with a pivot formed integrally on the tip of the hook, and a lever 120 serially apertured adjacent to one end to receive the pivots in operative relation whereby the hook members may be pulled together and the hook bearing shoulders thrown into mutual engagement to relieve 125 the said pivots.

6. In a tension take-up device of the character described a pair of hooks each having a long shank and a short cross shoulder to serve as a hoop part, in combination with 130

a lever having a short arm and a long arm, the short arm being pivoted at its ends to the tips of said shoulders respectively, and the long arm having means to prevent its 5 free end from swinging inward past the shank of the hook to the tip of which the inner pivot is connected, said lever being arranged for its long arm to swing down around the back of the last mentioned hook 10 for relaxing the device.

7. A quick acting adjustable take-up de-

vice for tension members comprising a turnbuckle having a two-section link, in combination with a U-shaped lever having the outer ends of its arms pivoted each to the corresponding adjacent parts of the link sections in operative take-up relation and arranged for snap over action as the lever is swung past its critical point. 15

Signed at Jacksonville this sixth day of 20 March 1922.

WILLIAM E. SULLIVAN.
